DOOR SEAL

Kenneth L. Pritchard, Baltimore, Md., assignor to The Duralite Manufacturing Company, Baltimore, Md., a corporation of Maryland

Application April 26, 1957, Serial No. 655,237

5 Claims. (Cl. 160—40)

This invention relates to a door seal and more particularly to a door seal having particular utility in connection with overhead doors adapted to be used in trucks, trailers, and the like.

Use of overhead type doors in large trucks and trailers permits them to be parked close together at a loading dock and close to the loading dock since the doors do not swing outwardly from the truck body or trailer. This obviously cuts down the time required to load or unload a given number of trucks or trailers which is one reason why more and more trucks and trailers are being equipped with overhead type doors instead of the conventional outwardly swinging doors. However, whether the doors be overhead doors or outwardly swinging doors, they must be sealed satisfactorily when they are closed in order to prevent damage to the cargo.

Inasmuch as overhead type doors for trucks and trailers conventionally run in tracks, freedom of movement with respect to any seal structure employed at the door opening is required in order to enable the door to be raised or lowered readily. Insofar as I am aware, this freedom of movement has generally been obtained by moving the door inwardly with respect to the seal structure as the door is opened to thereby free the door from dragging on the seal. Conversely, when the door is closed, it is moved against the seal. However, once a truck or trailer is loaded and the door closed, shifting of the cargo to the rear of the truck can result in binding the door against the seal so that it becomes extremely difficult to raise the door. The present invention overcomes this problem and, in general, provides an effective watertight and light-tight seal for overhead doors.

It is therefore an object of my invention to provide a new and improved door seal for overhead doors of the type adapted to be used on trucks and trailers.

It is another object of my invention to provide such a door seal which can be quickly and efficiently disengaged from sealing engagement with the door regardless of forces tending to press the door toward the seal.

It is a further object of my invention to provide such a door seal wherein the seal may be moved and locked swiftly into sealing engagement with the door.

It is a further object of my invention to provide such a door seal wherein a uniform sealing pressure is applied to the sealing member throughout its entire length.

Briefly described, a preferred embodiment of the present invention comprises a door seal structure wherein an elongated sealing member is supported and guided for substantially horizontal movement toward and away from the outer surface of the overhead door when the door is in its closed position. A vertically disposed actuating member is located between the sealing member and a stationary surface, such as a surface of a rear corner post of a truck or trailer body. This actuating member is capable of vertical movement relative to the sealing member. Also, the surfaces of the sealing member and actuating member which face each other are provided with

2

inclined cam surfaces at a suitable number of locations along their respective lengths.

An eccentric pin assembly is arranged to impart reciprocating vertical movement to the actuating member 5 which is translated into substantially horizontal movement of the sealing member by the inter-engagement of the respective inclined cam surfaces. The range of horizontal movement of the sealing member is such that, in its released position, it is located in spaced relationship 10 from the door surface, thus eliminating the possibility of any binding between the seal and door which might be occasioned by a shifting of the load within the cargo compartment.

Other objects and features of my invention will become 15 readily apparent by reference to the following specification taken in conjunction with the accompanying drawings.

In the drawings:

Fig. 1 is a rear view of a truck or trailer body provided 20 with a door seal according to the present invention;

Fig. 2 is a cross-sectional view through the body of Fig. 1 taken on the line 2—2 of Fig. 1;

Fig. 3 is a perspective view of portions of the sealing mechanism shown in Fig. 2 with certain parts omitted, 25 broken away, or shown in section to more clearly illustrate portions of the structure;

Fig. 4 is a cross-sectional view through the corner post of the body of Fig. 1, Fig. 4 being a section taken on line 5—5 of Fig. 1 but showing the sealing assembly in its 30 released position;

Fig. 5 is a cross-sectional view similar to Fig. 4 and taken on line 5—5 of Fig. 1 showing the sealing assembly in its sealing position; and

Fig. 6 is a partial cross-sectional view taken on the 35 line 6—6 of Fig. 4.

Inasmuch as the present invention has particular utility in connection with overhead doors for trucks or trailers, although it is not limited solely thereto, the drawings show the door seal structure as employed on a truck or 40 trailer body designated generally by the reference numeral 10. At the rear of body 10, two vertically disposed corner posts 12 and 14 are provided as part of the frame of body 10 and further serve to define the sides of the door opening which may be closed by an overhead door 16 of conventional construction. Door 16 includes a plurality of 45 horizontally extending segments 18 which are hingedly coupled to each other by conventional means, not shown. Door 16 is guided in movement relative to the body 10 by a plurality of rotatable rollers 20 (see Figs. 4 and 5) which are engaged within channel-shaped tracks 22 fixedly secured, as by welding, to the side walls of body 10. In the usual case, a spring driven roller and cable assembly indicated generally at 24 is employed to counter-balance the weight of the door.

50 My invention is especially directed to structure employed to seal the vertical side edges of door 16. Since the seal assembly is the same at both side edges of door 16, only the seal assembly associated with corner post 12 will be described in detail, it being understood that a similar assembly will be associated with corner post 14.

55 Corner post 12 may be conveniently formed from an elongated strip of angle iron, the rearwardmost leg 26 being provided with an inturned flange portion 28. A second vertically extending angle member 30 is secured 60 to the inner surface of leg 26 and, with flange 28, defines a vertically extending guide channel extending substantially the entire length of the inner surface of leg 26. An elongated channel-shaped sealing member 32 is received within the guiding channel defined by angle member 30 and flange 28 and extends upwardly from the 65 lower end of the guide channel to a location beyond the upper end of door 16 (see Fig. 2).

A resilient sealing strip 34 of suitable construction is secured along the inner surface of sealing element 32 for sealing engagement with door 16 as shown in Fig. 5. Sealing element 32 is supported within the guide channel by a pair of pins 36 (see Fig. 2) which extend inwardly respectively from angle member 30 and flange 28 into horizontal slots 38 formed in each leg of member 32 adjacent its upper end. The pin and slot connection supports member 32 within the guide channel for horizontal movement toward and away from sealing engagement with door 16. Suitable means, such as tension springs 39 may be employed to bias member 32 toward its retracted position.

Sealing member 32 is provided with a longitudinally extending cam member 40 which is fixedly secured to its inner surface. As best seen in Figs. 2 and 3, cam member 40 is provided with a plurality of rearwardly projecting inclined cam surfaces 42 which are located at spaced positions along cam member 40.

Cam surfaces 42 are located for sliding engagement with complementary inclined cam surfaces 44 which are formed on the inner surface of an elongated actuating member 46. Member 46 is located within the guide channel defined by angle member 30 and flange 28 and is maintained in position by a rearwardly projecting integral lug 48 which projects through a slot 50 provided in leg 26 of corner post 12. (See Figs. 4-6). Actuating member 46 is reciprocated vertically by manual operation of an actuating arm 52 which is pivoted for rotation about a pivot pin 54 supported in an ear 56 fixed to corner post 12. A second pivot pin 58 is fixed to hub 60 of arm 52 and projects from hub 60 through slot 62 in lug 48. The eccentric location of pin 58 with respect to the axis defined by the pivot pin 54 translates rotary movement of actuating arm 52 into vertical movement of actuating member 46. A fixed keeper member 64 is mounted upon corner post 12 to maintain actuating arm 52 in its lowermost position, this being the position of the arm when the seal is located in the sealing position shown in Fig. 5.

Operation of the sealing assembly is as follows: When door 16 is moved to its closed position, the sealing assemblies associated with both corner posts 12 and 14 will be in their normal or non-sealing position with the various parts disclosed in the positions shown in Figs. 4 and 6. Actuating arm 52 will be located in a substantially horizontal position, sealing member 32 will be located clear of the door as shown in Fig. 4, and actuating member 46 will be in its lowermost position.

To move sealing member 32 into sealing engagement with door 16, actuating arm 52 is manually rotated about pin 54 in a counter-clockwise direction from the position shown in Fig. 6. As arm 52 is rotated in this direction, pin 58 is likewise rotated in a counter-clockwise direction about the axis defined by pin 54. The vertical component of this rotary movement is transmitted by engagement of pin 58 with the walls of slot 62 into upward vertical movement of actuating member 46, no horizontal component being transmitted to member 46 by reason of the horizontal elongation of slot 62. Upward movement of actuating member 46 is translated into horizontal movement of sealing member 32 by the inner engagement of the inclined cam faces 44 and 42. Since actuating member 46 cannot move rearwardly because of the engagement of the rear surface of member 46 with the inner surface of leg 26, actuating member 32 is cammed horizontally into firm sealing engagement with the outer surface of door 16 as shown in Fig. 5 of the drawings. Upward vertical movement of sealing member 32 is prevented by the engagement of pins 36 with slots 38 in the legs of sealing member 32. Counterclockwise rotation of actuating arm 52 is continued until the arm is disposed in the position shown in Fig. 2 in which it may be engaged with keeper member 64 to hold the various parts in their sealing relationship.

The sealing "stroke" of sealing member 32 is selected to be such that at the sealing end of the stroke, sealing element 34 is compressed in the manner shown in Fig. 5 to achieve a watertight and light-tight seal between member 32 and the outer surface of door 16. As shown in Fig. 5, this engagement is selected to be firm enough to take up any lost motion which may be present between rollers 20 and tracks 22. When the parts are disposed in their sealing position, pin 58 is located in substantial horizontal alignment with pin 54. It will be noted that regardless of the magnitude of the force created by any rearward shifting of the truck or trailer load, the seal may be quickly and simply released. In fact, the forces created by rearward shifting of the load actually assist in releasing the seal.

While I have described one exemplary structural embodiment of my invention, it will be apparent to those skilled in the art that the disclosed embodiment is capable of modification. Therefore the foregoing description is to be considered exemplary rather than limiting and the true scope of my invention is that defined in the following claims.

I claim:

1. In an overhead door assembly for a truck body or the like including a pair of vertically disposed posts defining the sides of the door opening, and an overhead door guided in tracks mounted inwardly of said posts; a door seal assembly mounted on each of said posts for sealing engagement with the outer surface of said door when said door is in its closed position, each of said seal assemblies comprising a vertically disposed sealing member, means on the associated post supporting said sealing member for horizontal movement toward and away from the outer surface of said door, a vertical member mounted for vertical movement between said sealing member and said post, cooperating cam means on said sealing member and said vertical member for translating vertical movement of said vertical member into horizontal movement of said sealing member, and eccentric handle means on said post operatively connected to said vertical member for reciprocating said vertical member vertically with respect to said post to thereby move said sealing member into and out of sealing engagement with said door independently of door movement and without effecting substantial displacement of the door.

2. In an overhead door assembly for a truck body or the like including a pair of vertically disposed posts defining the sides of the door opening, and an overhead door guided in tracks mounted inwardly of said body from said posts; a door seal assembly mounted on each of said posts for sealing engagement with the outer surface of said door when said door is in its closed position, said seal assembly comprising a vertically disposed sealing member, means on the associated post for guiding said sealing member in horizontal movement only toward and away from the outer surface of said door, means supporting said sealing member within said guiding means for movement into and out of sealing engagement with said door, rearwardly facing inclined cam surfaces on said sealing member, vertically reciprocable means on said post engageable with said cam surfaces for moving said sealing member horizontally into and out of sealing engagement with said door and extraneous handle means on said post for actuating said vertically reciprocable means, said last mentioned means including means for locking said sealing member in sealing engagement with said door.

3. In an overhead door assembly for a truck body or the like including a pair of vertically disposed posts defining the sides of the door opening, and an overhead door guided in tracks mounted inwardly of said posts, a door seal assembly mounted on each of said posts for sealing engagement with the outer surface of said door when said door is in its closed position, said seal assembly compris-

ing a vertically disposed sealing member, means on the associated post for supporting said sealing member for horizontal movement toward and away from the outer surface of said door, a vertical member mounted for vertical movement between said sealing member and said post, rearwardly facing inclined cam surfaces on said sealing member, complementary forwardly facing inclined cam surfaces on said vertical member engageable with said cam surfaces on said sealing member to translate vertical movement of said vertical member into horizontal movement of said sealing member, and means on said post for reciprocating said vertical member vertically with respect to said post to thereby move said sealing member into and out of sealing engagement with said door independently of the position of said door and independently of any vibratory movement of said door.

4. In an overhead door assembly for a truck body or the like including a pair of vertically disposed posts defining the sides of the door opening, and an overhead door guided in tracks mounted inwardly of said posts; a door seal assembly mounted on each of said posts for sealing engagement with the outer surface of said door when said door is in its closed position, said seal assemblies each comprising a vertically disposed sealing member, means on the associated post for guiding said sealing member toward and away from the outer surface of said door, means supporting said sealing member within said guiding means for horizontal movement into and out of sealing engagement with said door, rearwardly facing inclined cam surfaces on said sealing member, a vertical member mounted for vertical movement between said post and said sealing member and including forwardly facing inclined cam surfaces engageable with cam surfaces on said sealing member, said vertical member being movably supported upon said post and operable to drive said sealing member into sealing engagement with said door, eccentric means on the associated post for vertically actu-

ating said vertical member, and means on the associated post for locking said sealing member in sealing engagement with said door.

5. In an overhead door assembly for a truck body or the like including a pair of vertically disposed posts defining the sides of the door opening, and an overhead door guided in tracks mounted inwardly of said posts; a door seal assembly mounted on each of said posts for sealing engagement with the outer surface of said door when said door is in its closed position, said seal assembly comprising a vertically disposed sealing member, means on the associated post for supporting said sealing member for movement toward and away from the outer surface of said door, a vertical member mounted for vertical movement between said sealing member and said post, rearwardly facing inclined cam surfaces on said sealing member, complementary forwardly facing inclined cam surfaces on said vertical member engageable with said cam surfaces on said sealing member to force said sealing member into sealing engagement with the outer surface of said door upon vertical movement of said vertical member in one direction, said sealing member being releasable from sealing engagement with the outer surface of said door upon movement of said vertical member in the opposite direction, and means connected to said vertical member for moving said vertical member in said one direction to thereby move said sealing member into sealing engagement with said door, and releasable locking means for locking said vertical member against movement in said opposite direction from a position wherein said sealing member is in sealing engagement with said door.
